UNITED STATES PATENT OFFICE.

OTTO WALTHER, OF CHEMNITZ, GERMANY.

EMBROIDERING-MACHINE.

1,106,429.

Specification of Letters Patent. Patented Aug. 11, 1914.

Application filed December 31, 1912. Serial No. 739,572.

To all whom it may concern:

Be it known that I, Otto WALTHER, a citizen of the United States, and resident of Chemnitz, Germany, have invented certain new and useful Improvements in Embroidering-Machines, of which the following is a specification.

This invention relates to an improved apparatus for the manufacture of crochet goods, and the main characteristic of the invention consists in the fact that, like in machine-embroidery, crochet work is produced on a stretched fabric base, which is moved corresponding to a design, while for obtaining loose crochet-goods the fabric is after its working burnt-out either by means of acids, chlorid or the like, or by the drying process known in the art.

The crochet-meshes can be produced on the fabric base in different ways: in the example shown on the accompanying drawings, for instance a particularly appropriate apparatus is diagrammatically represented, by means of which chain-stitch meshes can be produced on the fabric base.

Figure 1 shows the apparatus in a sectional side view, Fig. 2 in a plan view; for sake of clearness, certain parts are omitted in this figure and only the first and last separate contrivances of one row are shown. Fig. 3 shows a separate contrivance in a longitudinal section and on a larger scale, while Figs. 4 to 8 show the way how the meshes are formed.

The whole apparatus is to be mounted in a machine-frame not shown on the drawing, which is constructed like that of an embroidery machine and provided with a pantograph. In front of and behind the crochet-frame 1, which is fitted with the stretched fabric base, consisting of wool-cloth or the like, and which corresponds exactly to the known embroidery-frame, the working mechanisms proper are arranged; on the front sides the needle-slides 3 are movably mounted, while on the rear side of the crochet-frame 1 the supports 4 for the bearings of the looper supporting heads are located. In front of the needle-slides 3, two ledges 5 and 6 are mounted, of which the ledge 5 is fitted with the bobbins 7 and the ledge 6 with the thread-brakes 8 and the thread-guides 9. Behind the support 4, links 11 (Figs. 1 and 2) are pivotally connected to an arm fixed on an axle 10, to which an oscillatory motion is imparted,

said links being adapted to operate the push-rod 12 for the looper which is movably mounted in the looper-supporting head 13. As clearly shown in Fig. 3, the bearing-bolt 14 of the looper-supporting head 13 has a central boring for guiding the push-rod 12 therein, which by double joints 15, 16 is so attached to the rotary axle 17 of the hook-shaped looper 18, which is fixed thereon, that the looper must, upon movement of the push-rod 12, accomplish a swinging movement.

The needle-slide 3 carries the movably mounted needle-holder 19, with needle 23, which, being hollow, serves at the same time as a thread-guide; the needle-slide 3 is, by driving means not shown on the drawing, alternately moved to and fro toward the fabric base in the direction of arrows I (Figs. 1 and 3). A springy guide 21, which is screwed below the needle-slide 3 on a ledge 20, bears close upon the fabric base 2, and each looper supporting head 13 carries a stitch-plate 22 as a counter-bearing for the guide 21 which is provided with needle-holes.

To effect the required rotary movements of the needle 23 and looper 18, the needle-holders 19 as well as the bearing-bolts 14 of the looper supporting head 13 are fitted with worms 24 and 26 respectively, which are driven by worm-wheels 25 and 27, the axles 28 and 29 of which are connected with bevel-gearings (Fig. 2). The axles 28 and 29 are driven from a spindle 35, which is adapted to act by a bevel-wheel 30 on the bevel-wheels 31, 32, 33 and 34. A main requirement of the apparatus is that the needles 23 and the loopers 18 are set in rotation in a uniform way and in the same direction in order to produce a reliable loop-formation. To aid in the working of the bevel-gearing 31, the axles 28, 29 are at their other ends connected by an auxiliary bevel-gearing 32^a, 36, 37 and 38, and it must be noted that, owing to the forward and backward movement of the needles 23 or needle-slides 3 respectively, also the driving axle 28 belonging thereto must participate with its worm wheels 25 in this movement, for which purpose the axles 39 of the bevel-wheels 33 and 37 are slidable in axial direction (arrows II, Fig. 2) within the hollow axles 40 of the wheels 31 and 36, a rotary movement of the axles 39 within the axles 40 being prevented by a known slot-

and-pin connection between the axles, this being not shown as it is clear without further illustration.

The formation of loops and meshes, which, 5 formed along the fabric base 2, according to the design desired, represents the crochet-work, is effected like the known chain-stitch-mesh formation and can be seen from Figs. 4, 5 and 8: The advanced needle 23 10 pierces the fabric base 2 and, upon its return movement, the looper-point of the looper 18, which swings always toward the middle of the looper supporting-head, catches the thread-loop 41, as the push-rod 15 12 is drawn outward by the double-armed levers 11. The looper 18 holds the loop fast, drawing the same upon its return movement somewhat downward, until upon the next advance of the needle 23 the loop 41 gets gradually loose for the passage of the needle and falls off from the looper-point. A particular characteristic of the invention is that the looper 18 and the needle 23 accomplish 20 rotary movements in the same direction and the looper 18 swings with its point always 25 toward the middle of the looper supporting head, to which also the needle is directed. The thread is drawn to that direction in which the pantograph-pin is moved, and in 30 the same direction also the looper-point must swing and, therefore, needle and looper must be turned accordingly. Supposing, for instance, that the pantograph-pin is, after formation of the thread-loop on the looper 35 (Fig. 5) and upon a complete return of the needle (for instance into a position between that shown in Figs. 5 and 8), moved in the direction of arrow III (see front view of the looper 18, Fig. 6,) also the needle 23 40 and the looper 18 must, for obtaining a cor-

rect loop-formation, receive a corresponding rotary movement, influenced by the hand-operated axle 35 of the apparatus (see front view of the looper, Fig. 7 and needle position, Fig. 8).

45

On a crochet-machine, according to the present invention, two or even three rows of separate contrivances can, like on embroidery machines, be mounted at different heights, so that under the given circumstances the largest possible number of single crochet goods can be produced on the fabric base. By a following burning-out of the fabric by means of acids, chlorid or similar means, for instance by the known drying process, correspondingly multiple loose 50 55 crochet goods are obtained, which from hand crochet-work can be hardly distinguished.

I claim:

In an embroidering machine, the combination of reciprocating and rotary needle-slides, needles secured thereto, swinging and rotary loopers to co-act with the needles for the formation of chain-strokes, a driving spindle, worms connected to the slides and 60 65 loopers, worm-wheels to gear with the worms, bevel-gearings to connect the worm-wheels with the driving spindle, and means to allow part of the bevel-gearings to participate in the reciprocating movement of the slides, substantially as and for the purpose set forth.

In testimony whereof I have hereunto set my hand in the presence of two subscribing witnesses.

OTTO WALTHER.
